Attorney.

UNITED STATES PATENT OFFICE.

AUBREY FREDERICK SPENCER, OF MARGATE, ENGLAND, ASSIGNOR OF ONE HALF TO ADOLPH ROSENBERG, OF LONDON, ENGLAND.

HEEL FOR BOOTS AND SHOES.

No. 853,198.

Specification of Letters Patent.

Patented May 7, 1907.

Application filed October 16, 1906. Serial No. 339,209.

To all whom it may concern:

Be it known that I, AUBREY FREDERICK SPENCER, a subject of the King of Great Britain, residing at Margate, in the county of Kent, England, have invented new and useful Improvements in the Heels of Boots and Shoes, of which the following is a specification.

The object of the present invention is to construct a heel for boots and shoes which is easily attachable and detachable, is safe in use, is resilient, wears evenly, and in which the rubber or other resilient pad, when such is used, is durable.

15 The invention is illustrated in the accompanying drawings, in which

Figure 1 is a side elevation of the improved parts of a heel which are attached to an ordinary solid leather heel, this latter being indicated in dotted lines. Fig. 2 is a plan of the same. Fig. 3 is a section on the line 3—3 of Fig. 2. Fig. 4 is a plan of a metal plate or lift to which the leather tread or lift is fixed. Fig. 5 is a plan of a rubber or other resilient 25 pad or lift. Fig. 6 is a side elevation of a smaller metal plate.

A heel constructed according to the present invention has a leather tread or lift *a*, which is the surface in contact with the ground when in use, and is provided with a hole *a'* to admit a screw driver to act upon the head of the screw by which the whole is secured to the boot or shoe. Above this leather lift *a*, and riveted or otherwise fixed 30 to it, is a thin metal lift *b* formed with a number of holes *b'*, each surrounded by a rim *b''* forming a hollow stud. On the top of this metal lift *b* is an inner rubber or other lift *c* having a number of perforations *c'* to receive 35 the hollow studs *b''* of the metal lift *b* which studs *b''* help to retain the rubber or other lift *c* in position. The rubber or other lift *c* has a large, preferably triangular, aperture *c''* at its center and depressions or grooves *c'''* communicating with the aperture *c''*.

A small metal plate *d*, provided with extending arms *d'*, fits the aperture *c''* and grooves *c'''*. This small metal plate has downwardly projecting edges *d''* which fit 40 into the aperture *c''*. This metal plate has small holes in the arms *d'*, through which

small screws or pegs are passed to fix it to the heel of the boot or shoe. A central screw *e* is passed through holes in the parts *a*, *b*, *c* and *d*, and fixes them all together and at the same time allows the parts to rock on the head of the screw *e* as the rubber is compressed on one side in walking. The head of the screw *e* fits into a hollow upwardly projecting stud *b''* of somewhat conical form formed in the metal lift *b*. I preferably employ two washers, a metal one, *f*, and a rubber one, *f'*, which are interposed between the head of the screw *e* and the hollow stud *b''*. The small metal plate *d* has a tapped socket *d''* to receive part of the screw *e*.

The inner rubber lift *c*, being much thicker than the small metal plate *d*, leaves an air space in the aperture *c''*, which adds to the resiliency of the heel. When it is not desired to have a resilient heel, the rubber pad *c* may be replaced by one made of leather.

What I claim as my invention is:

1. In a heel for boots and shoes, the combination of an outer leather lift, a metal lift to which the outer leather lift is directly attached, an inner lift having depressions, a metal plate of smaller size than the inner lift inclosed therein fitting the aforesaid depressions and having a screw-threaded socket and a central screw engaging in said threaded socket and securing all the parts together, substantially as set forth.

2. In a heel for boots and shoes, the combination of an outer leather lift, a metal lift, to which the leather lift is fixed, having a number of projecting hollow studs, an inner lift engaged by said projecting hollow studs, so that they help to retain it in position, a metal plate of smaller size than the inner lift inclosed therein, having a screw-threaded socket, and a fixing screw passing through one of the hollow studs in the metal lift and engaging in the threaded socket in the smaller metal plate, to secure all the parts together, substantially as described.

3. In a heel for boots and shoes, the combination of an outer leather lift, a metal lift to which the leather lift is fixed, a number of hollow studs carried by said metal lift, one of said studs being adapted to receive the head of the fixing screw, a perforated inner

lift adapted to receive said studs and having depressions, a smaller metal plate having extending arms fitting in said depressions, downwardly projecting edges and a screwed 5 socket on said smaller plate, and a fixing screw screwing into said screwed socket, substantially as set forth.

In witness whereof I have hereunto set my hand in presence of two witnesses.

AUBREY FREDERICK SPENCER.
